UNITED STATES PATENT OFFICE.

DAVID HINDAHL, OF CHICAGO, ILLINOIS, ASSIGNOR TO NATIONAL DUMP CAR COMPANY, OF CHICAGO, ILLINOIS, A CORPORATION OF MAINE.

DOOR-ACTUATING MECHANISM FOR GENERAL-SERVICE CARS.

1,178,012.

Specification of Letters Patent.

Patented Apr. 4, 1916.

Application filed May 5, 1913. Serial No. 765,619.

To all whom it may concern:

Be it known that I, DAVID HINDAHL, a citizen of the United States, residing at Chicago, in the county of Cook and State of Illinois, have invented certain new and useful Improvements in Door-Actuating Mechanism for General-Service Cars, of which the following is a specification.

My invention relates in general to freight cars, and more particularly to door actuating mechanism for freight cars of the type known as "general service" cars.

The practicability of general service cars depends largely upon the efficiency of the mechanism for operating the drop doors which form the principal part of the car floor. It is essential that the operating mechanism should tightly close the doors to prevent leakage of the lading; should securely support the doors in closed position so as to avoid accidental dumping of the lading; and should permit the dropping of the doors to discharge the lading. It is further essential that the door operating mechanism should be strong and durable in construction and at the same time simple in operation.

The object of my invention is to provide an improved operating mechanism for the drop doors of freight cars, which will possess the desirable characteristics above referred to.

My invention will be more fully disclosed hereinafter with reference to the accompanying drawings, in which the same is illustrated as embodied in a convenient and practical form, and in which—

Figure 1 is a side elevational view of a portion of one end of a freight car, parts thereof being broken away; Fig. 2, a detail plan view taken on line 2—2, Fig. 1; Fig. 3, an end elevational view, parts being broken away; Fig. 4, an enlarged cross sectional view on line 4—4, Fig. 1, showing the door in open position; Fig. 5, a detail sectional view showing the door lifted into partially closed position; and Fig. 6, a view similar to Fig. 5, showing the door completely closed and supported in closed position.

The same reference characters are used to designate the same parts in the several figures of the drawings.

Reference letter A indicates the center sill, which may be of any suitable construction, such, for instance, as of the "box girder" type.

B indicates the front sill of the car, and C one of the cross bearers or transverse members of the underframe.

D designates one of the end walls of the car, and E one of the side walls. 60

F indicates one of the drop doors which is pivotally supported by hinges G upon the center sill. The door F is adapted to be swung upwardly about its inner edge into a closed position flush with the plane of the floor of the car, or to be swung downwardly, to the position shown in Fig. 4.

H designates a fixed floor strip which overlies the transverse underframe member C and projects on the opposite sides thereof 70 so as to form stops against which the adjacent side edges of the adjacent doors engage when closed.

A car of the construction above described is one well-known and does not in itself embody my invention, but is merely illustrated and described in order that the construction and operation of my improved door actuating mechanism may be fully disclosed. 75

It will be obvious that my invention may be applied to cars of other specific constructions than that above described.

Supported by the transverse members C of the underframe is a longitudinal rotary shaft L connected by means of chains N with 85 the swinging edges of the drop doors F. The shaft L may be conveniently supported upon the outer ends of the transverse members of the underframe beneath the inwardly inclined portion e of the overlying car side.

K designates a semi-circular bearing surrounding the shaft L above each of the transverse members of the underframe so as to rotatably support the shaft thereon. 95

The ends of the chains N may be conveniently connected to the doors by means of screw threaded eye-bolts n which are adjustably secured to a bracket O rigidly fastened beneath the door adjacent its swinging edge, one of such brackets being provided adjacent each side edge of the door so that each door may be operated by two chains N. Each bracket O may be conveniently secured to a longitudinal Z-beam F' shown in dotted lines in Fig. 1, which extends beneath each door adjacent its side edge to impart strength thereto. 100

P designates a second longitudinal shaft rotatably supported upon the ends of the 110

transverse members of the underframe and preferably beneath the inwardly inclined portion *e* of the overlying car side. The bearing brackets *K* which retain the shaft *L* on the ends of the transverse beams *C* may also be extended to overlie the shaft *P*, as shown in Fig. 2. The end of the shaft *P* which projects beyond the end sill *B* of the car is made square, as shown at *p*, to be engaged by a lever for imparting rotary motion to the shaft.

Q designates a ratchet wheel fixed to the end of the shaft *P* adjacent the outer surface of the end sill *B* with which coöperates a pawl *q* to retain the shaft *P* in any positions to which it may be oscillated. A yoke *R* is non-rotatably secured to the shaft *P* adjacent each side edge of each door. The yoke *R* preferably comprises a sleeve 20 which surrounds and is clamped to the shaft *P* and depending links between the lower ends of which is supported an anti-friction roller *S*. In alinement with each of the yokes *R* is a bracket *T* fixed to the edge of 25 the door preferably by underlying and being secured to the end of the adjacent reinforcing *Z*-beam *F'*. A lug *t* is formed on each bracket *T* and projects beyond the edge of the door in position to extend between the 30 depending links *R'*, *R*² of the adjacent yoke *R* and to rest upon the roller *S* carried thereby.

The operation of my improved door actuating mechanism is as follows: When the 35 doors are in the open position shown in Fig. 4 and it is desired to close them, a suitable lever is applied to the squared end *l* of the shaft *L* to impart rotary motion thereto and to thereby wind the chains *N* thereon. A 40 pawl *m* pivotally mounted on the end sill *B* coöperates with a ratchet wheel *M* on the end of the shaft *L* to retain such shaft in the positions to which it may be rotated and thereby support the doors in the positions 45 to which they have been lifted by the winding of the chains *N* on the shaft. When the doors are elevated to the position shown in Fig. 5, the lug *t* engages the roller *S* and thereby oscillates the yoke *R* outwardly so 50 as to permit the door to be completely closed, as shown in Fig. 6. When the door is completely closed, the lug *t* is in a position immediately above the roller *S*. The shaft *P* is then oscillated by applying a suitable 55 lever to the squared end *p* thereof so as to swing the several yokes *R* inwardly and thereby locate the rollers *S* beneath the respective lugs *t* on the doors. It will be observed that the under surface of each of the 60 lugs *t* is preferably curved upwardly so as to facilitate the inward movement of the co-operating roller *S* beneath the same, such movement of the roller beneath the lug also serving to tightly wedge the door closed and 65 compensate for any slight differences in

the length of the two chains *N* connected to each door.

When it is desired to open the doors and permit the discharge of the lading, the pawl *q* is disengaged from the ratchet wheel *Q* 70 and the shaft *P* then oscillated in a direction to swing the lower ends of the several yokes *R* outwardly, thereby removing the rollers *S* from beneath the respective lugs *t*. The disengagement of the pawl *m* from the 75 ratchet *M* permits the doors to swing by gravity into open position.

From the foregoing description it will be observed that I have invented an improved door actuating mechanism for the drop 80 doors of freight cars, which will not only close the doors but will wedge them tightly closed and securely support them in load sustaining position.

It will be further observed that my improved door operating mechanism is exceedingly simple in operation, and hence can be readily actuated by the ordinary unskilled laborer employed for unloading freight cars.

I claim:

1. In a freight car, the combination with a drop door in the floor thereof, of a rotary shaft, means operatively connecting said shaft and door to effect the closing movement of the door when said shaft is rotated, a lug projecting beyond the swinging edge of said door and having an outwardly and upwardly curved under surface, a rock shaft extending transversely to the path of movement of said door, and a door support non-rotatably secured to said rock shaft and comprising radial spaced members between the free ends of which a roller is carried, whereby when the door is closed and the rock shaft oscillated the radial members of said support will straddle said lug and support its curved under surface upon said roller.

2. In a freight car, the combination with an underframe comprising transverse and longitudinal members, of a plurality of drop doors in the floor of said car, a rotary shaft journaled upon the ends of the transverse members of the underframe, means operatively connecting said shaft and doors to effect the closing of the doors when said shaft is rotated, a pair of lugs projecting outwardly from the swinging edge of each door, each lug having an outwardly and upwardly curved under surface, a rock shaft mounted upon the ends of the transverse members of the underframe adjacent said rotary shaft, and door supports projecting radially from and non-rotatably secured to said rock shaft, each of said supports comprising a pair of radial members between which is carried a roller, whereby when said rock shaft is oscillated one of said supports will engage each of said lugs and effect the

final closing and positive support of the doors.

3. In a freight car, the combination with a drop door in the floor thereof, of a rotary shaft, means operatively connecting said shaft and door to effect the closing of the door when the said shaft is rotated, a lug member projecting beyond the swinging edge of said door, a rock shaft extending 10 transversely to the path of movement of said door, door-supporting means carried by said shaft and oscillatable therewith, said

means being arranged to coact with said lug member to support said door in closed position, said lug member being constructed and arranged to move said supporting means out of its path of travel during closing movement of said door. 15

In testimony whereof, I have subscribed my name.

DAVID HINDAHL.
